UNITED STATES PATENT OFFICE.

WILLIAM E. PETTY, OF PROVIDENCE TOWNSHIP, BUENA VISTA COUNTY, IOWA.

DRIER.

1,387,168.

Specification of Letters Patent. Patented Aug. 9, 1921.

Application filed May 12, 1919. Serial No. 296,314.

To all whom it may concern:

Be it known that I, WILLIAM E. PETTY, a citizen of the United States of America, and resident of Providence township, Buena Vista county, Iowa, have invented a new and useful Drier, of which the following is a specification.

The object of this invention is to provide an improved construction for driers.

10 A further object of this invention is to provide improved means for ventilating a drier.

A further object of this invention is to provide improved means for controlling a 15 ventilator on a drier at the initial end thereto.

A further object of this invention is to provide improved means for controlling a 20 ventilator on a drier at the terminal end thereof.

A further object of this invention is to provide improved means for constructing a drier in sections for convenience in taking 25 down and assembling and transporting, some of said sections nesting within each other.

A further object of this invention is to provide improved means for deflecting air currents within a drier.

30 A further object of this invention is to provide improved means for suspending articles, such as ears of corn, within a drier.

A further object of this invention is to provide an improved construction for the 35 floor of a drier.

My invention consists in the construction, arrangement and combination of elements hereinafter set forth, pointed out in my claims and illustrated by the accompanying 40 drawing, in which—

Figure 1 is an elevation of one of my improved devices, the door, one of the windows, and a terminal ventilator being shown in open position. Fig. 2 is a vertical section 45 of the apparatus shown in Fig. 1. Fig. 3 is a plan of the apparatus shown in Fig. 1. Fig. 4 is a horizontal section on the indicated line 4—4 of Fig. 1, the door being closed and the deflector being omitted. Fig.

50 5 is a bottom plan view of the apparatus on an enlarged scale. Fig. 6 is a diagram illustrating means of separating the wall in sections of various sizes in order that the sections when separated may nest in compact form. Fig. 7 is a cross section on a reduced

scale illustrating the means employed for suspending objects within the drier, the same means serving to connect sections of the wall and roof together. Fig. 8 is an enlarged detail section illustrating the construction of a portion of the roof and terminal ventilating devices. Fig. 9 is a detail section illustrating the construction of a portion of the wall, floor and initial ventilating device. Fig. 10 is a detail section illustrating the construction of a portion of the wall, floor and door, together with an initial ventilating device operating through the door.

In the construction of the apparatus as shown the floor structure is formed in one section, the wall is formed in three sections, the roof is formed in one section including the terminal ventilators, and said sections are adapted to be assembled and connected as herein described in detail to the completion of a unitary structure having a door providing ingress and egress, various windows having means for controlling the passage of air therethrough, and terminal ventilators, the latter being operated by devices extending in proximity to the door. In addition to these general subdivisions of the structure, a deflecting device is mounted 75 removably and replaceably within the wall, 80 spaced from the floor and susceptible of being manipulated through the doorway.

The floor structure preferably comprises a ring member 10, angular in cross section and circular in plan view, floor boards 11 90 over-lying and connected in any suitable manner to said ring member and angle bars 12 arranged radially of and secured at their outer ends to said ring member beneath the floor boards, said angle bars being connected rigidly centrally of the ring member, whereby a rigid, unyielding and strong device is produced susceptible of carrying any load placed in the drier. A wall is mounted on the peripheral portion of the 100 floor structure and preferably is composed of 3 sections—13, 14, 15 (Fig. 6) of different sizes; the section 14 being adapted to nest in the section 15 and the section 13 being adapted to nest in the section 14 for convenience in storing or transporting the drier. The wall generally is composed of studding 16 resting on and rising from the floor boards 11 at stated intervals, which studding are overlaid on the outside by a 110

sheathing 17 of sheet metal and on the inside by a sheathing 18 of sheet metal, thus providing air spaces between the studding on the one hand and the sheathing 17, 18 on the other hand. The sheathing 18 preferably stops against the upper surface of the floor boards 11, while the sheathing 17 preferably overlaps both the floor boards and the periphery of the ring member 10. The wall sections preferably are secured together by the provision that adjacent marginal portions of the sheathing 17 and 18 shall overlap at the lines of separation of the sections, the overlapping portions of the sheathing being secured by removable means such as screws 19 extending through them and seated in studding 16. Thus the various sections of the wall may be assembled and connected as shown in Fig. 6 and, by removing the screws 19, the several sections may be separated and transported or stored as desired. The several sections of the wall preferably are secured to the floor structure in a manner to be removed and replaced relative thereto, and for this purpose I have shown, in Fig. 9, angle-irons 20, one for each studding, adapted to be placed in the angle formed by the sheathing 18 and floor boards 11 and be secured by screws 21 to the studding and sheathing and by bolts 22 to the floor structure, said bolts extending through the floor boards 11 and angle bars 12 and spaced co-incident with said studding and angle bars as shown in Fig. 5. The sheathing 17 is formed with a series of horizontal slots 23 arranged in vertical rows spaced so that said slots will be located wholly between studding 16 and the lowermost slot in either row is spaced above the floor boards 11 a considerable distance. The slots 23 are formed by striking out portions of the metal of which the sheathing 18 is formed, and said portions are bent inwardly of the drier and stand in upwardly inclined positions and are curved laterally on an arc of the circumference of the sheathing 18, thus forming lips or flanges 24. The wall of the drier is formed with a plurality of windows 25 located in the sheathing 17 and wholly within the spaces between the studding 16 and also located wholly in a horizontal row beneath the lowermost slot 23 of each vertical row of said slots. A screen or section of wire netting 26 is mounted over each window 25 and secured to the inner face of the sheathing 17 between the studding 16 for the purpose of excluding vermin and insects from the drier. Slide bearings 27 are mounted on the outer face of the sheathing 17 on opposite sides of each window 25 and shutters 28, one for each window, preferably made of single pieces of sheet metal, are slidingly mounted in said bearings. Each shutter 28 is supported by a chain 29 secured at one end thereto

and adapted to be detachably connected to a hook 30 for the purpose of suspending said shutter at any desired elevation in either open or closed position. A hood 31 is provided for each window, is secured to the sheathing 17 and overhangs the shutter and chain thereon for the purpose of shedding rain and snow away from the window. A door opening is provided at a suitable point in the wall of the drier wholly between two of the studding 16 and the wall is provided with a header 32 above said opening and with sections of the sheathing 17, 18 at either end thereof. A door 33 is constructed and hinged, and may be fastened in any desired manner, within the door opening and said door preferably is formed of side studding 16', a sill 16'' and a header 16''' suitably connected with and supporting sheets 17' and 18' of sheathing material. The door 33 preferably is provided with a window on its sheathing section 17' and slots in its sheathing section 18' and a hole 23' in the header 16''' matching a hole 32' in the header 32 when the door is closed, thus providing ventilation through said door, under control of a shutter 28 as has been described in connection with remaining portions of the wall, the sheet 17' of sheathing preferably overlapping marginal portions of the sheathing on the wall surrounding the door so as to bridge the crack of the door when the same is closed. The roof structure preferably comprises a ring member 34, angular in cross section and adapted to rest on and bridge the spaces between the upper ends of the studding 16, rafters 35 mounted on and rising in an inclined plane from said ring member and a cupola surmounting said rafters, the rafters being overlaid with roofing plates 36, preferably of sheet metal connected to said rafters by standing seams. A spider is thrown across the upper end of the wall and preferably is composed of metal bars 37 either straight or bent in any suitable manner and adapted to be connected at the center of the drier to form a unitary structure susceptible of sustaining all the weight to be applied thereto. End portions of the bars 37 preferably are twisted into a plane at right angles to the plane of the greatest transverse dimension of the bar and split longitudinally, thus forming two lugs at one end of each of said bars; one lug 38 being adapted to overlie and be riveted to the ring member 34, while the other lug 39 is bent downward and overlaps the upper portion of the inner sheathing 18 and is adapted to be secured by a screw 40 extending through said lug and sheathing and seated in the upper end of a studding 16. Thus provision is made for strengthening the wall of the drier laterally, for strengthening the roof laterally, for supporting objects to be dried and for

connecting said roof and wall rigidly yet detachably. It is to be understood that the spider forms a part of the roof structure and is removable from the wall as a part of 5 said structure, together with the ring member 34. Any articles to be dried such as ear corn may be supported in any suitable manner on or suspended from the spider. The cupola is constructed generally of spaced 10 rings 41, 42 of substantially the same size; the lowermost ring being supported by a ring of sheet metal 43 carried by the rafters 35 and the uppermost ring supporting a ring of sheet metal 44, the latter ring of 15 sheet metal carrying a roof 45 composed of sheets of metal arranged in conical form and connected by standing seams; there being spaced strips 46 arranged to connect the rings 41, 42. Angular frames 47 are mounted 20 between and overlap at the top and bottom on the rings 41, 42 and said frames are overlaid by plates 48, thus comprising a door, marginal portions of said plates overlapping ribs on the rings 41, 42. The 25 doors are carried by hinges 49, one hinge for each door, secured to the sheet metal rings 44. The door frames and doors bridge the spaces between the vertical strips 46 and provide ventilators for the cupola. A 30 screen 50, of annular form, is mounted within and carried by the rings 41 and 42 and extends across the openings provided for the ventilator doors, thus prevent the entrance of vermin, birds and other objectionable life to the drier from the top when 35 the ventilators are open. Ropes 51, one rope for each ventilator, are secured at their outer ends to eyes 52 located in the center of the lower portion of the respective ventilators and said ropes extend from said 40 eyes through guiding eyes 53 arranged at the eave of the roof 45, thence through notches in the sheet metal ring 44 and thence through the spider and are joined 45 preferably beneath said spider to a rope 54 carried to a cleat 55 on the wall of the drier adjacent to the doorway therein. It is the function of the ropes 51 and 54 to open the ventilator doors and hold them open 50 when desired and similar ropes 51' are connected to said ventilator doors on the inside and extend to a similar cleat on the opposite side of the doorway for the purpose of closing the ventilator doors and holding them closed when desired; the means for opening and closing the ventilators being alternately operated manually. Sometimes it is desirable to supply artificial heat to the drier and to that end angle-irons 56 may be 55 secured to the studding and extend on the inside of the sheathing 18 in an annular row immediately below the lowermost slots 23; and a deflector formed of opposing and mating leaves 57, 58 of sheet metal, is 60 mounted horizontally in the drier and rests 65 at its margin on said angle-irons and is spaced at its periphery from said sheathing. The diametrical portion 59 of the member 57 overlaps beneath the corresponding portion of the member 58 and said members 70 are concave and semi-conical respectively and are arranged in inverted position as shown. Thus the complete deflector occupies an inverted conical relation in the drier and serves to deflect toward the wall of the 75 drier any artificial heat which may be supplied beneath the apex thereof such as by a lamp, not shown, resting on the floor boards 11.

In practical use the apparatus may be employed for drying articles or objects, for smoking meat or for storing various kinds of merchandise. When the apparatus is employed as a drier or for smoking meat the objects or articles preferably are suspended 80 from the bars 37 of the spider and out of contact with the wall. Any suitable means may be employed for suspending the articles and numerous examples thereof related to seed corn are now common and well known. 90 Ordinarily it is sufficient to suspend the articles within the drier, open the ventilator doors in the cupola, close the door 33 and open a sufficient number of windows to admit air to the apparatus. The air is admitted 95 through the windows to the space between the sheathing of the walls; passes thence through slots 23 to the interior of the drier, rises around and in contact with the objects to be dried and passes off through the ventilators, normal and sluggish circulation of air being maintained through the course just described by reason of the draft created through difference in altitude of the windows and cupola. The air currents through 100 the drier may be regulated by closing to any desired degree the windows and ventilator doors selectively.

When the objects to be dried are soft and contain considerable moisture it sometimes 110 is desirable to apply artificial heat to warm the air currents or raise the temperature within the drier. In such event the members 57, 58 are inserted one at a time through the doorway and positioned as shown in Fig. 2, 115 a space existing between the rim of the deflector and the adjacent sheathing 18. A lamp of common form may be located in a well-known manner on the center of the floor of the drier and direct the discharge 120 from its flue against the apex of the deflector to the end of establishing and maintaining heated air currents through the space surrounding the deflector, which air currents join with normal air currents entering the 125 drier, as above described, and raise the temperature and reduce the humidity thereof to the end of more rapidly drying the contents of the apparatus. Ventilation is provided for the lamp beneath the deflector by leak- 130

age of air through the joint between the walls and floor of the device, there being no effort made to have said joint air tight.

The deflector may be omitted and fire pots 5 containing meat smoking elements may be arranged on the floor of the drier when it is desired to cure meat in the apparatus.

I claim as my invention—

1. A drier provided with walls consisting 10 of inner and outer shells and cross members between them forming a series of separated intervening flues, a central top ventilator, the interior being divided by a horizontal deflector to form an upper storage compartment 15 and a lower heating compartment in communication at the periphery of the deflector, a portion of the wall between two of said cross members and including less than the full height of the wall being hingedly 20 mounted to form an entrance door, communication being provided between the top of the flue in said hingedly mounted portion and the flue in the remaining portion of the wall above the same, each flue, including the 25 door portion, being provided in its outer shell near the bottom with screened air inlet openings and also being provided in its inner shell with horizontal slots affording communication with said storage compartment.
- 30 2. A drier provided with walls consisting of inner and outer shells and cross members between them forming a series of separated intervening flues, a central top ventilator, the interior being divided by a horizontal deflector to form an upper storage compartment 35 and a lower heating compartment in communication at the periphery of the deflector, said deflector being inclined from its center upwardly to its periphery, a portion 40 of the wall between two of said cross members and including less than the full height of the wall being hingedly mounted to form an entrance door, communication being provided between the top of the flue in said 45 hingedly mounted portion and the flue in the remaining portion of the wall above the same, each flue, including the door portion, being provided in its outer shell near the bottom with screened air inlet openings and also being provided in its inner shell with horizontal slots affording communication with said storage compartment.
- 50 3. A drier provided with walls consisting of inner and outer shells and cross members 55 between them forming a series of separated intervening flues, a central top ventilator, the interior being divided by a horizontal deflector to form an upper storage compartment and a lower heating compartment in 60 communication at the periphery of the deflector, a portion of the wall between two of

said cross-members and including less than the full height of the wall being hingedly mounted to form an entrance door, communication being provided between the top 65 of the flue in said hingedly mounted portion and the flue in the remaining portion of the wall above the same, each flue, including the door portion, being provided in its inner shell with horizontal slots affording communication with said storage compartment and also being provided in its outer portion with screened air inlet openings, and dampers slidingly mounted on said outer shell and adapted to close said screened openings. 70

4. A drier provided with walls consisting of inner and outer shells and cross members between them forming a series of separated intervening flues, a central top ventilator, the interior being divided by a horizontal 80 deflector to form an upper storage compartment and a lower heating compartment in communication at the periphery of said deflector, a portion of the wall between two of said cross members and including less than the full height of said wall being hingedly 85 mounted to form an entrance door, communication being provided between the top of the flue in said hingedly mounted portion and the flue in the remaining portion of the wall above the same, each flue, including the door portion, being provided in its outer shell near the bottom with screened air inlet openings and also being provided in its inner shell with horizontal slots affording communication with said storage compartment, portions of the inner shell extending upwardly and inwardly partially 90 across said slots.

5. A drier according to claim 1 and distinguished in this: that the top ventilator is formed with screened openings and closing doors are hingedly mounted on said top and adapted to close said screened openings 100 at times.

6. A drier according to claim 1 and distinguished in this: that the wall is formed in separable sections adapted to be assembled and secured to a floor and the central top ventilator is separately formed and 110 adapted to be assembled on the wall.

7. A drier according to claim 1 and distinguished in this: that the drier is provided with a floor separately formed and adapted to support the wall in detachable 115 relation, said floor being formed with radial angle bars rigidly connected and adapted to support and brace the body of the floor.

Signed at Des Moines, in the county of Polk and State of Iowa, this 23rd day of April, 1919.

WILLIAM E. PETTY.
